UNITED STATES PATENT OFFICE.

KATHARINE F. EIKER AND FRISBEY G. EIKER, OF WASHINGTON, DISTRICT OF COLUMBIA.

HOSE-SUPPORTER.

No. 880,130.

Specification of Letters Patent.

Patented Feb. 25, 1908.

Application filed August 1, 1907. Serial No. 386,649.

To all whom it may concern:

Be it known that we, KATHARINE F. EIKER and FRISBEY G. EIKER, citizens of the United States, residing at Washington, District of Columbia, have invented a new and useful Hose-Supporter and Abdominal and Hip Depressing Appliance, of which the following is a specification.

This invention relates to hose supporters, combined with means for causing pressure upon the abdomen for the purpose of preventing unsightly projection thereof; it also relates to means for retaining the corset in place and causing a light pressure upon the hips and other portions of the human figure, for the same general purpose of improving the appearance of the form thereof; it also relates to combination garters, stocking supports, suspenders &c.

20 The object of this device is to provide a means for drawing the corset inwardly so as to prevent the abdomen, hips &c. from becoming too prominent, thereby giving the form a better shape and appearance; at the same time providing a garter and stocking support that will not injure or tear the most delicate fabric.

A further object is to more firmly retain the corset in the most desirable position.

30 The hose supports now in use for the purpose sometimes tear the cloth in case any great strain is brought to bear upon it for the purpose of causing pressure of the corset, to which the supports are attached. In order to permit considerable tension to be placed upon the supporters for the above mentioned purpose, we make our hose supporters of greater length and provide them at their lower ends—below the point of attachment with the stocking—with a band which encircles the leg below the knee.

40 We attain these objects by the appliance illustrated in the accompanying drawing, in which—

45 Figure 1—is a perspective view of the appliance as applied to the human figure; Fig. 2—is an elevation of one-half of the appliance, the portion that is fitted to one leg; Fig. 3—is a view of the sliding connection 50 of the long supporting band with the buckle for adjusting same to the corset; Fig. 4 is a fragmentary view showing the mode of attaching the hose supporters to the rear or inside face of the tension straps. Fig. 5 is a 55 fragmentary detail illustrating a convenient

mode of attaching the hose supporter clasp to its strap.

Similar letters refer to similar parts throughout the several views.

A, is the main supporting tension strap or band; this band A passes loosely through the buckle B, whereby the said strap may adjust itself to the changing positions of the limbs of the wearer. The lower ends of the strap A are attached securely to the leg encircling band C. The leg encircling band C is provided with an adjustable buckle D to permit of a snug engagement with the leg below the knee. The buckle B is adjustably secured on the tab E, which is secured to the 70 corset in any suitable manner.

The stocking supporter clasps F are provided with straps G, which at their upper ends are adjustably attached to the straps A by the buckles H. In order that the hose supporters may be secured to either side of the tension strap, to admit of the stocking being worn either inside or outside of the leg band C, the said hose supporters, comprising the clasps F and straps G are detachably connected to the buckles H on the tension straps A, so that the straps G may be secured to the front of the buckles H, as shown in Fig. 2 or to the rear of said buckles as indicated in Fig. 4.

55 The tabs E are attached to the corset I, at the points shown, or at any other part of the corset, at the convenience and wish of the wearer. The means of attaching may be ordinary stitching or any other method of attachment may be used according to the convenience or desire of the user.

I, is the corset, which may be of any of the usual forms now in use. The buckles B are provided with a loop, or supporting bar J, on 95 which the main supporting tension band A loosely slides. The upper portion K, of the buckle B, may have any of the usual forms which will permit the same to be firmly attached to the tab E at the desired position.

100 Additional pieces or tabs E', may be attached to the corset just above the hips, in order to cause a pressure on these parts. These pieces E' may also be connected with the bands C by a single strap L, shown 105 broken off at the bottom. Or, if preferred, a double strap similar to straps A may be used for these hip depressing pieces.

110 In applying this device, the end portions of the strap A are so placed on the leg as to run

diagonally from the buckle B to the leg encircling band C at the opposite sides of the knee, as shown in the drawings. The buckle B is then adjusted to the proper height to give the desired tension, or strain. This tension or strain may be such as the wearer desires, so as to cause the requisite pressure of the lower portion of the corset upon the abdomen or hips. The stocking engaging 10 clasps F are next attached to the upper ends of the stockings, and the buckles H are adjusted upwardly or downwardly to such a position as to properly support the stocking. The leg encircling band C is next adjusted to 15 such tightness, by means of the buckle D, as will cause a firm engagement with the leg below the knee to prevent the encircling band sliding upwardly over the knee.

Having thus described our invention, we 20 claim as new and desire to secure by Letters Patent:

1. In a combined hose supporter and body shaping appliance, the combination of a tension strap or band connected at its upper end 25 to a corset or other like article of apparel and having means for securing the lower ends thereof to the leg, and a detachable stocking engaging device adapted to be secured to either side of said tension strap.
2. In a combined hose supporter and body shaping appliance, the combination of a tension strap or band connected at its upper end to a corset or other like article of apparel and having means for securing the lower end at 35 the leg, a clasp or buckle adjustable on said tension strap, and an adjustable stocking engaging device adapted to be secured to either side of said tension strap.
3. In a combined hose supporter and body 40 shaping appliance, the combination of a tab attached to a corset or other like article of apparel, a clasp adjustably secured to said tab, a leg band, and a tension strap connect-

ing the leg band with the adjustable clasp and having a sliding connection with said 45 clasp.

4. In a combined hose supporter and body shaping appliance, the combination of a tab attached to a corset or other like article of apparel, a clasp adjustably secured to said tab, a loop carried by said clasp, a leg band, and a tension strap connected at its two ends to the leg band and having a sliding engagement with the loop at its intermediate portion. 55

5. In a combined hose supporter and body shaping appliance, the combination of a tab attached to the corset or other like article of apparel, a clasp adjustably secured to said tab, a loop carried by said clasp, a leg band, a tension strap connected at its ends to the leg band and having a sliding engagement with the loop at its intermediate portion, and stocking engaging devices secured to said tension strap. 60

6. In a combined hose supporter and body shaping appliance, the combination of a tab attached to the corset or other like article of apparel, a clasp adjustably secured to said tab, a loop carried by said clasp, a leg band, a tension strap connected at its ends to the leg band and having a sliding engagement with the loop at its intermediate portion, an adjustable clasp or buckle secured to the tension strap, and a detachable stocking engaging device carried by said adjustable buckle and adapted to be secured to either side of the same. 75

In testimony whereof, we have hereunto set our hands in the presence of two witnesses. 80

KATIE F. EIKER.
FRISBEY G. EIKER.
